UNITED STATES PATENT OFFICE.

WILLIAM C. WILLIAMS, OF MARSHALLTOWN, IOWA, ASSIGNOR OF THREE-EIGHTHS OF HIS RIGHT TO BENJAMIN T. FREDERICK AND ONE-EIGHTH TO JOHN M. GILCHRIST, BOTH OF SAME PLACE.

LIFTING-JACK.

SPECIFICATION forming part of Letters Patent No. 224,499, dated February 10, 1880.

Application filed December 12, 1879.

To all whom it may concern:

Be it known that I, WILLIAM C. WILLIAMS, of Marshalltown, in the county of Marshall and State of Iowa, have invented certain new and useful Improvements in Lifting-Jacks; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a perspective view of the device. Fig. 2 is a vertical central section from top to bottom. Fig. 3 is a bottom plan with slide removed.

This invention relates more especially to that class of lifting-jacks designed for use in making repairs on railroad-tracks; and the principal novelty consists in the construction of the device, whereby it is adapted to be applied readily and conveniently to the rail to be operated on, and to afford means for raising the rail any desired height, from the very least to the full extent of the lifting scope, all as will now be more fully set out and explained.

In the drawings, A denotes the body of the jack, within which is fitted and applied the lifting part B. This can be moved up and down in the socket a of the body A by means of the wheel C operating on the screw-threaded extension b, which projects up from B through the top part of A.

On one side of the part B are notches b'. These are designed for the pawl or lever D to engage upon. This pawl is applied through the slot or opening a' in the rear side of the body A.

Upon the lower end of the lifting part B is the foot b'', which projects outwardly from the part B and through the slot e in the front of body A. In the up-and-down movement of part B the foot b'' will rush in said slot.

In use, it is designed to place the jack so that the foot b'' can be inserted under one of the rails of a railroad-track; then, either by means of wheel C or the lever or pawl D, the part B can be raised, according as it may be desired to lift the rail more or less.

When the part B is raised by the lever or

pawl D it may be fixed or held at the point desired by turning the wheel.

While the lever or pawl D can be jointed or attached to the body of the jack, it will probably be found best to have it separate from it, and, as a longer or shorter one can be used, an ordinary railroad-track or pinch bar can be readily substituted for it.

The extension b of the lifting part B may, if desired, be double-threaded, and its socket in C also so threaded. This will give some desired advantage in certain instances.

The jack can be easily taken apart, as for packing or repairs, by screwing off wheel C and drawing out the slide a'', which covers the bottom of socket a.

The jack is preferably made of metal, and usually of such shape and size as above explained.

By this invention is furnished a small, compact, and strong tool or device for use in repairing railroads. It combines all the advantage of the screw-and-lever lift. It can be applied most readily and operated easily and exactly, as may be required, to raise the rail in the very least degree, or to lift it entirely out of place.

Having thus described my invention, what I consider new, and desire to secure by Letters Patent, is—

1. In a lifting jack, the body A, having socket a, opening a', and slot e, and lifting part B b'', provided with notches b', and adapted to be raised by wheel C and pawl D, substantially as and for the purposes set forth.

2. In a lifting-jack, substantially as described, the detachable wheel C and removable slide-cover a'', substantially as and for the purpose set forth.

3. In a lifting-jack, substantially as described, the combination of body A with lifting part B, having screw-threaded extension b, notches b', and foot b'', and the wheel C, substantially as and for the purpose set forth.

In testimony that I claim the foregoing I have hereunto set my hand this 29th day of November, 1879.

WM. C. WILLIAMS.
